UNITED STATES PATENT OFFICE.

STANLEY JAROZS, OF DETROIT, MICHIGAN, ASSIGNOR OF ONE-HALF TO ANTHONY GRZEZINSKI, OF DETROIT, MICHIGAN.

FIRE-ALARM GUARD.

1,150,945.

Specification of Letters Patent. Patented Aug. 24, 1915.

Application filed April 17, 1915. Serial No. 21,963.

To all whom it may concern:

Be it known that I, STANLEY JAROZS, a citizen of the United States of America, residing at Detroit, in the county of Wayne 5 and State of Michigan, have invented certain new and useful Improvements in Fire-Alarm Guards, of which the following is a specification, reference being had therein to the accompanying drawings.

10 This invention relates to a fire alarm guard, and the primary object of my invention is to furnish the door or closure of a fire alarm box with novel means for temporarily detaining the operator or puller of 15 the box, whereby the identity of the operator or puller can be ascertained by firemen, policemen and other officials.

Another object of this invention is to provide fire alarm boxes with devices which will 20 ultimately eliminate the nefarious practice of unscrupulous persons, particularly juveniles, who at the expense of a city call out the fire department as a joke or for amusement or exciting purposes.

25 A further object of this invention is to furnish the door of a fire alarm box with an automatically actuated hand cuff or gripping device adapted to hold a hand inserted in the box to send an alarm, the hand being 30 held without injury thereto but in such a manner that the operator or puller of the box cannot escape until an official arrives to release the device.

The above and other objects are attained 35 by a simple, durable and inexpensive mechanical construction that will be hereinafter described and then claimed, and reference will now be had to the drawing, wherein—

Figure 1 is a front elevation of a fire 40 alarm box in accordance with this invention; Fig. 2 is a side elevation of the same partly broken away and partly in section; Fig. 3 is a cross sectional view of the fire alarm box showing the inner side of the door there- 45 of, and the gripping device in a released or retracted position; Fig. 4 is a similar view showing the gripping device in a locked position; Fig. 5 is a fragmentary perspective view of a portion of the device, and Fig. 6 50 is a similar view of another portion of the device adapted to be used in connection with that portion shown in Fig. 5.

In the drawing, 1 denotes a box, having a hinged door 2 provided with a lock 3 adapted 55 to secure the door 2 whereby the contents of

the box cannot be tampered with. The box may be of the well known "Gamewell" or "Star" type and is adapted to contain an alarm sending mechanism which can be easily operated or pulled, the mechanism forming no part of this invention, therefore I have only illustrated the operating shaft or arbor 4 of such mechanism, the shaft terminating in proximity to the inner side of the door 2 and having a notch 5, whereby 60 the reduced end 6 of a turn-button 7 can be interlocked with said shaft. The turn-button 7 is operatively held by the door 2 and adjustably mounted upon the inner end of said turn-button is a curved crank 8, the 65 purpose of which will presently appear. The top of the door 2 has an outwardly extending bearing 9 and journaled in said bearing is a sleeve 10, which has the outer end thereof provided with a gripping arm 70 11 terminating in a curved wrist portion 12.

Journaled in the sleeve 10 is a shaft 13 which has the outer end thereof provided with a gripping arm 14, similar to the arm 11 and these arms extend through a strap 15 80 connected to the inner side of a casing 16. The casing 16 is rectangular in elevation with the upper end thereof rounded and inclosing the bearing 9. The casing has apertured bosses 17 at appropriate places whereby screws 18 can be employed for connecting the casing to the door 2, said screws entering the bosses 17 from the inner side of the door, and thereby preventing easy removal of the 85 casing. The casing has the front wall 90 thereof provided with a hand opening 19 through which a hand is inserted to turn the button 7 and send in an alarm signal. The wrist portions 12 of the gripping arms 11 and 14 are disposed at the sides of the hand 95 opening 19 within the casing and the wrist of a hand inserted in the casing can be gripped and held when the arms 11 and 14 are brought together, as shown by dotted lines in Fig. 4.

The inner ends of the sleeve 10 and the shaft 13 are provided with curved cranks 20 and 21 respectively connected by a coiled retractile spring 22 which pulls the gripping arms 11 and 14 to a closed position, as shown 100 in Fig. 4. The curved cranks 20 and 21 have the ends thereof provided with a series of notches or teeth 23 adapted to be engaged by the hooked ends of bell cranks 25 and 26 105 pivotally supported by the inner side of the 110

door 2. The short arms of these bell cranks are pivotally connected by a link 27 having a rigid extension 28 adapted to be engaged by the curved crank 8 of the turn button 7. 5 To retain the curved crank 8 normally in engagement with the extension 28 of the link 27 a pivoted member 29 is employed, said member being connected to the inner side of the door 2 and pressed by a conventional 10 form of spring 30, also carried by the inner side of the door. In addition to this spring there are springs 31 carried by the inner side of the door 2 and engaging the bell cranks 25 and 26 to retain the hooked ends of said 15 bell cranks in engagement with the curved cranks 20 and 21, particularly while the turn-button 7 is being restored to its normal position after having been turned to sound an alarm.

20 A clockwise movement of the turn-button 7 not only places the fire alarm signal mechanism in operation, but the bell cranks 25 and 26 until the toothed ends of the curved cranks 20 and 21 are released, thereby 25 allowing the coiled retractile spring 22 to rock the shaft 13 and the sleeve 10 and bring the gripping arms 11 and 14 together. This is accomplished by having the gripping arm and curved crank of the shaft 13 upon one 30 side of the vertical axis of the box and the gripping arm and crank of the sleeve 10 upon the opposite side, the crank and arm of the shaft and sleeve simultaneously moving in the same direction.

35 As the curved crank 8 of the turn-button is restored to normal position by the fire alarm signal mechanism, the springs 31 shift the hook ends 24 of the bell cranks 25 and 26 into engagement with the notches or teeth 40 of the curved cranks 20 and 21, thus locking the gripping arms 11 and 14 in a closed position, until the door 2 is unlocked, opened and the arms 11 and 14 restored to normal 45 position. The strap 15 within the casing 16 limits the opening movement of the gripping arms 11 and 14, consequently the hook ends 24 of the bell cranks 25 and 26 can be set under the ends of the curved cranks 20 and 21 to hold the gripping arms in a re- 50 tracted position.

It is thought that the operation and utility of the device will be apparent without further description, and while in the drawing there is illustrated a preferred embodiment of my invention, it is to be understood that the structural elements are susceptible to such variations and modifications as fall within the scope of the appended claims.

60 What I claim is:—

1. The combination with a fire alarm box adapted to contain a signal mechanism and having a hinged door provided with means adapted to set in motion the mechanism within said box, of a casing connected to

said door and provided with a hand hole, gripping arms within said casing adjacent to the hand hole thereof, curved cranks at the inner side of said door, and movable simultaneous with said gripping arms, bell 70 cranks carried by the inner side of said door adapted to engage said curved cranks and retain said gripping arms in a retracted position, and means carried by the inner side of said door and actuated by the first mentioned means to shift said bell cranks, release said curved cranks and engage said curved cranks to lock said gripping arms in a closed position.

2. The combination with a fire alarm box 80 having a hinged door and means carried by said door adapted for placing said box in operation, of a casing connected to said door and having a hand opening whereby easy access can be had to said means, gripping 85 arms in said casing adjacent to the hand hole, curved cranks in said box movable simultaneously with said gripping arms, means engaging said curved cranks to retain said gripping arms in a retracted position, and means actuated by the first mentioned means adapted to shift the last mentioned means whereby said gripping arms 90 can close to a locked position.

3. The combination with a fire alarm box 95 having a hinged door provided with means adapted to facilitate placing said box in operation, of a bearing carried by said door, a sleeve journaled in said bearing, a shaft journaled in said sleeve, gripping arms carried by the outer ends of said sleeve and said shaft, a casing carried by said door and inclosing said gripping arms, said casing having a hand hole adjacent to said gripping arms to permit of the means of said 100 door being actuated, curved cranks carried by the inner ends of said sleeve and said shaft, means engaging said curved cranks adapted to retain said gripping arms in a retracted position, and means actuated by 105 the means of said door to release the last mentioned means whereby said gripping arms 110 can close upon a hand inserted in the hand hole of said casing.

4. The combination with a fire alarm box 115 having a door provided with means adapted for placing the fire alarm box in operation, of a sleeve journaled in said door, a shaft journaled in said sleeve, curved cranks carried by the inner ends of said sleeve and 120 said shaft, bell cranks carried by the inner side of said door, and normally engaging said curved cranks to retain said cranks in a retracted position, a casing carried by said door and provided with a hand hole, means 125 on the outer ends of said sleeve and said shaft adapted to grip a hand inserted in the hole of said casing, and means actuated by the means of said door adapted to shift said bell cranks whereby said curved cranks 130

allow the means of said sleeve and said shaft to grip the hand inserted in said casing.

5. The combination with a fire alarm box having a door provided with a turn button, 5 of a casing carried by said door and provided with a hand hole, a bearing carried by said door, a sleeve journaled in said bearing, a shaft journaled in said sleeve, gripping arms carried by the outer ends of said 10 sleeve and said shaft adjacent to the hand hole in said casing, curved cranks carried by the inner ends of said sleeve and said shaft, bell cranks carried by the inner side of said door and normally engaging said 15 curved cranks to retain said gripping arms in a retracted position, means actuated by

said turn-button to shift said bell cranks and release said curved cranks, means connecting said curved cranks adapted to close said gripping arms upon the hand inserted in 20 said casing to operate said turn-button, and means engaging the bell cranks adapted to shift said bell cranks into engagement with said curved cranks to lock said gripping arms in a closed position. 25

In testimony whereof I affix my signature in presence of two witnesses.

STANLEY JAROZS.
